ANTENNA

Robert M. Silliman, Silver Spring, Md., assignor
to the United States of America as represented
by the Secretary of War

Application December 10, 1945, Serial No. 634,095

12 Claims. (Cl. 250—33)

1

This invention relates to electrical apparatus. More particularly it relates to an antenna for transmitting and receiving electrical energy at very high radio frequencies, the matching section making connection between the antenna, and the transmission line being part of the antenna structure.

The matching sections of the prior art used to connect an antenna to its transmission line have been external to the antenna structure. Hence, these sections have been exposed to the danger of breakage and have thus impaired the useful service of the apparatus with which the matching section is associated. Efforts of the prior art to protect the matching section by giving it additional strength by methods such as reinforcing it by housing have proved impractical, due to the resulting bulk of the apparatus. This is especially disadvantageous when the apparatus is to be used on aircraft where the weight of radio apparatus is always a major factor in its design.

It is an object of the present invention to provide an antenna structure which is in the same housing with its matching section and which is enclosed by the same nacelle.

It is also an object of the present invention to provide an antenna which surrounds the coaxial transmission line matching section which conveys electrical energy to it when it is a transmitting antenna or conveys electrical energy from it when the antenna is used to receive radio frequency signals.

It is another object of the present invention to provide an antenna for operation over a wide range of radio frequencies in which a matching section is folded into the interior of the antenna structure.

It is a further object of the present invention to provide an antenna inside of which is a one-quarter wavelength matching section folded so that the outside surface of the antenna is a continuation of the inside surface of the outer conductor of the matching section.

Generally, this invention comprises a wide band antenna in which a matching section is folded into the interior of the antenna structure without impairing the efficiency of the antenna. The outside surface of the antenna is continuous with the inside surface of the outer conductor of the matching section, and the folding of this same conductor at the top of the antenna structure joins it with the inside conductor of the transmission line.

Other objects, features, and advantages of this invention will suggest themselves to those skilled

5 2

in the art and will become apparent from the following description of the invention taken in connection with the accompanying drawing which is a cross-sectional view of an antenna surrounding its matching section and constructed in accordance with the principles of the present invention.

The antenna and its matching section are generally designated on the drawing by 10. The 10 actual configuration of this structure may be more fully appreciated by visualizing it as a figure of revolution about the axis A—A. The antenna, which consists of a conical section 21 and a cylindrical section 11, is connected to the 15 matching section which consists of an outer conductor 12, inner conductor 15 and the dielectric 20 which lies between them.

R. f. energy is conveyed to the antenna and matching section by connecting an external 20 coaxial transmission line (not shown) to the terminal 13. The r. f. energy is conveyed to the matching section by the center conductor 14 and outer conductor 15 of a coaxial line within the antenna structure. The upper end of the center 25 conductor 14 is electrically connected to the antenna 11 by screw 16. The center conductor is supported by insulating bushing 17 at the bottom and by insulating bushing 18 at the top. The adapter 19 electrically connects the conductor 14 to the matching section conductor 12. In the matching section conductor 12 is insulated from the conductor 15 by means of the dielectric 20, which serves also as a mechanical support. The 30 conical conducting section 21 is soldered to the lower end of the matching section conductor 12 and is soldered also to the tabs 22 which extend from the lower portion 11 of the antenna. The entire assembly is covered by a housing 23 of insulating material. The housing is fastened to the baseplate 24 by screws 25. The structure of the matching section is connected mechanically to the baseplate by adapter 26 which is soldered thereto. The antenna is supported in spaced 35 relationship to the housing by means of spring fingers 27. The entire assembly is connected to a mounting 28, such as the skin of an aircraft, by the screws 25.

Considering the operative relationship of the parts described above, the antenna 10, 21 is a 40 shaped member mounted in fixed spaced relationship to the conductive member 24 and as such presents an impedance Z_1 which is measurable between 21 and 24 in the region of adjacency of these parts.

The radio frequency energy for exciting the

antenna is applied to a coaxial transmission line 14, 15 which has a characteristic impedance Z_2 and the applied energy may be said to flow inside this line.

Since the transmission line 14, 15 is placed inside the antenna 11, 21 in the cavity formed by conductor 12, the outside surface of conductor 15 and the inside surface of conductor 12, together with the dielectric of 20 which lies between, now serves as a coaxial line section of impedance Z_0 to match the transmission line to the antenna.

The relation between the impedances involved at the frequency of which the section 12 is a one-quarter wavelength is as follows:

$$Z_2 = \frac{Z_0^2}{Z_1}$$

Let us suppose that the matching section is by the design proportions of its length, spacing and dielectric content made one-quarter wavelength in length at 217 megacycles. At this frequency the impedance Z_1 presented by the antenna to the matching section 12 is approximately 16 ohms. The matching section 12 has a characteristic impedance Z_0 of approximately 40 ohms at about 400 megacycles. If this matching section having an impedance of 40 ohms is used to match the 16 ohms presented by the antenna to it to 100 ohms a standing wave ratio not exceeding two to one results on the transmission line at any frequency from 190 to 650 megacycles. Such a wide frequency range coupled with the desirable physical characteristics of this device has made the use of this device particularly advantageous on aircraft.

The antenna structure hereinbefore described has been designed primarily for use with aircraft and because of its compact design is particularly suitable therefore. The antenna may, of course, be used in other environments. It has also been found that, although desirable, it is not necessary for the matching section to be a quarter wavelength long for any of the frequencies within the band for which the antenna was designed to operate.

From the preceding description it will be clear that in accordance with the invention, the antenna structure comprises a hollow, shaped conductive member in spaced relationship adjacent to a conductive surface, this member being re-entrant in the region of adjacency to form a cavity therein, the outer shape and size of said member having proportions to provide at the region of adjacency a predetermined antenna impedance characteristic over a chosen band of frequencies. A coaxial line of chosen characteristic impedance and having an inner and an outer conductor, passes through an opening in the conductive surface in the aforementioned region of adjacency and into the cavity. The outer surface of the outer conductor of the transmission line is conductively contiguous with the conductive surface and the inner conductor is conductively connected at a point to the inner surface of the cavity. The inner surface of the cavity and the outer surface of the outer conductor which lies within the cavity have chosen dimensions and spacings thereby constituting a line section which is effective to match the impedance of the line to the antenna impedance.

It will be apparent that there may be deviations from the invention as described which still fall fairly within the spirit and scope of the invention.

Accordingly I claim all such deviations which fall fairly within the spirit and scope of the invention as identified in the hereinafter appended claims.

What is claimed is:

1. A wide band antenna assembly comprising an antenna having a truncated conical portion and a cylindrical portion, a coaxial transmission line located within said portions, a cylindrical matching section comprising a cylindrical conductor concentric with said coaxial line, the outer surface of said line forming the inner conductor of said section, means electrically connecting one end of said cylindrical conductor to the truncated end of said conical portion and the other end to the inner conductor of said coaxial line.

2. A wide-band antenna assembly as claimed in claim 1 in which said matching section is a quarter wavelength for one of the frequencies within the operating band of said antenna.

3. A wide band antenna assembly as claimed in claim 1 in which said antenna is enclosed within a housing of insulating material.

4. A wide-band antenna assembly comprising an antenna having a truncated conical portion and a cylindrical portion, a conducting ground plane, a coaxial transmission line located within said portions a coaxial matching section comprising a cylindrical conductor concentric with said coaxial line, the outer surface of said line forming the inner conductor of said section means at a first end of said cylindrical conductor electrically connecting the outer conductor of said matching section to the truncated end of said conical portion and the inner conductor of said matching section to said ground plane and means at a second end of said matching section for coupling said matching section to said coaxial line.

5. A wide band antenna assembly comprising an antenna having a cylindrical portion closed at one end by a conductive base, and a truncated conical portion, the base of said conical portion being electrically connected to the open end of said cylindrical portion, a first tubular conductor disposed within said antenna connecting the truncated end of said conical portion to the base of said cylindrical portion, a second tubular conductor disposed concentrically within said first conductor and insulated from said first conductor and said base, and a third conductor disposed concentrically within said second conductor and insulated therefrom, said third conductor making electrical contact with said conductive base whereby said second and third conductors form a coaxial line for transferring energy to said antenna and said first and second conductors form a coaxial matching section for matching said coaxial line to said antenna.

6. An antenna assembly as claimed in claim 5 wherein the space between said first and second conductors is filled with a solid dielectric material to increase the effective electrical length of said matching section.

7. An antenna assembly as claimed in claim 5 said assembly further comprising means for supporting said first and third conductors from said second conductor whereby said antenna assembly is supported by said second conductor.

8. An antenna assembly as claimed in claim 5 said assembly further comprising a conductive ground plane, means for supporting said second conductor from said ground plane, and means for supporting said first and said third conductor from said second conductor whereby said an-

tenna is supported by a predetermined distance above said conductive ground plane.

9. An antenna structure comprising a hollow shaped conductive member supported in spaced relationship adjacent to a conductive surface, said member being re-entrant in the region of adjacency to form a cavity therein, the outer shape and size of said member having proportions to provide at said region of adjacency a predetermined antenna impedance characteristic over a chosen band of frequencies, a coaxial line of chosen impedance having an inner and an outer conductor, said line passing through an opening in said surface in the said region of adjacency and into said cavity, the outer surface of said outer conductor being conductively contiguous with said surface and said inner conductor being conductively connected at a point to the inner surface of said cavity, said inner surface of said cavity and the outer surface of said outer conductor which lies within said cavity having chosen dimensions and spacings to constitute a line section which effectively matches the impedance of said line with the impedance of said antenna over said chosen band of frequencies.

10. An antenna structure comprising a hollow shaped conductive member supported in spaced relationship adjacent to a conductive surface, said member being re-entrant in the region of adjacency to form a cavity therein, the outer shape and size of said member having proportions to provide at said region of adjacency a predetermined antenna impedance characteristic over a chosen band of frequencies, a coaxial line of chosen impedance having an inner and an outer conductor, said line passing through an opening in said surface in the said region of adjacency and into said cavity, the outer surface of said outer conductor being conductively contiguous with said surface and said inner conductor being conductively connected at a point to the inner surface of said cavity, a dielectric support for said member filling the space between said inner surface of said cavity and the outer surface of said outer conductor which lies within said cavity, said surfaces having chosen dimensions and spacings to constitute a line section which effectively matches the impedance of said line and the impedance of said antenna over a chosen band of frequencies.

11. An antenna structure comprising a hollow shaped conductive member supported in spaced relationship adjacent to a conductive surface, said member being re-entrant in the region of adjacency to form a cavity therein, the outer shape and size of said member having proportions to provide at said region of adjacency a predetermined antenna impedance characteristic over a chosen band of frequencies, a coaxial line of chosen impedance having an inner and an outer conductor, said line passing through an

opening in said surface in the said region of adjacency and into said cavity, the outer surface of said outer conductor being conductively contiguous with said surface and said inner conductor being conductively connected at a point to the inner surface of said cavity, dielectric material filling the space within said cavity, said inner surface of said cavity and the outer surface of said outer conductor which lies within said cavity having chosen dimensions and spacings to constitute a line section which effectively matches the impedance of said line and the impedance of said antenna over a chosen band of frequencies and more closely matches at a chosen frequency at the lower end of said band.

12. An antenna structure comprising a hollow shaped conductive member supported in spaced relationship adjacent to a conductive surface, said member being re-entrant in the region of adjacency to form a cavity therein, the outer shape and size of said member having proportions to provide at said region of adjacency a predetermined antenna impedance characteristic over a chosen band of frequencies, a coaxial line of chosen impedance having an inner and an outer conductor, said line passing through an opening in said surface in the said region of adjacency and into said cavity, the outer surface of said outer conductor being conductively contiguous with said surface and said inner conductor being connected at a point to the inner surface of said cavity, dielectric material filling the space within said cavity, said inner surface of said cavity and the outer surface of said outer conductor which lies within said cavity having chosen dimensions and spacings to constitute a line section of a quarter wave length at a chosen frequency thereby to match the impedance of said line and the impedance of said antenna over a chosen band of frequencies.
